CLAIM

The ornamental design for a laser assistant, as shown and described.

DESCRIPTION

FIG. 1 is a top, front and side perspective of the laser assistant of the invention.

FIG. 2 is a bottom, front and side perspective of the laser assistant of the invention.

FIG. 3 is an elevational view of one side of the laser assistant of the invention.

FIG. 4 is a front elevational view of the laser assistant shown in FIG. 3.

FIG. 5 is a top plan view of the laser assistant shown in FIG. 3.

FIG. 6 is an elevational view of the opposite side of the laser assistant of the invention, to that shown in FIG. 3.

FIG. 7 is a back elevational view of the laser assistant shown in FIG. 6; and,

FIG. 8 is a bottom plan view of the laser assistant shown in FIG. 6.

The broken line showing portions of a laser assistant is included for the purpose of illustrating environmental structure and forms no part of the claimed design.
